UNITED STATES PATENT OFFICE.

CHARLES W. BAILEY, OF PHILADELPHIA, PENNSYLVANIA, ASSIGNOR TO THE BAILEY,
BANKS & BIDDLE COMPANY, OF PHILADELPHIA, PENNSYLVANIA, A CORPORATION
OF PENNSYLVANIA.

DESIGN FOR A RING.

Application filed August 31, 1922. Serial No. 3,600. Term of patent 7 years.

To all whom it may concern:

Be it known that I, CHARLES W. BAILEY, my new design.
a citizen of the United States, residing in the city and county of Philadelphia, State
of Pennsylvania, have invented a new, original, and ornamental Design for Rings, of which the following is a specification, reference being had to the accompanying drawing, forming part thereof.

Figure 1 is a top view of a ring showing

Figures 2 and 3 are elevations respectively of opposite edges thereof.

I claim:—

The ornamental design for a ring, as shown.

CHARLES W. BAILEY.
